Application January 26, 1938, Serial No. 187,037

6 Claims. (Cl. 158—28)

This invention relates to improvements in control apparatus and particularly to control apparatus for fuel burning systems.

An object of the invention is to provide a control system, for electrically operated fuel burning apparatus, comprising a device for controlling energization of the apparatus and a control circuit for the device, the control circuit having a switch therein which is adapted to be opened by the device when the device causes deenergization of the apparatus and which is closed automatically by a time mechanism but only after a predetermined time after the opening thereof by the device to thereby insure a time lapse before reenergization of the apparatus in the event there is a demand for operation of the fuel burning apparatus substantially immediately after a cessation of demand.

Another object of the invention is to provide a control system for an electrically operated fuel burning apparatus, including an ignition circuit having mechanism for controlling the same, which system comprises a device for controlling energization of the apparatus and a control circuit for controlling the device, the control circuit having a switch therein adapted to be opened when the apparatus is deenergized, and comprises timing mechanism for reclosing the control circuit switch after the ignition circuit is conditioned for operation by the control mechanism therefor.

A still further object of the invention is to provide a control system for a fuel burning apparatus, including an electric ignition circuit having a time mechanism for opening the same, which system comprises a device for causing energization and deenergization of the apparatus, the device being controlled by a control circuit having a switch therein, and the device being operative, when the device operates to deenergize the apparatus, to open the control circuit switch and to close the ignition circuit, and comprises timing means for reclosing the switch in the control circuit after a predetermined time period.

Other and further objects and advantages will be apparent from the following description, reference being had to the accompanying drawings wherein a preferred form of embodiment of the present invention is clearly shown.

In the drawings:

Fig. 1 is a diagrammatical showing of the control apparatus in an oil burner system, the system being inoperative, and

Fig. 2 is similar to Fig. 1, and shows the parts of the control apparatus in the positions assumed during normal operation of the fuel burner.

A transformer relay device 10 is provided for controlling the circuit of the fuel feeding apparatus, and to also provide current for a low voltage control circuit for controlling operation of the device. The transformer relay device 10 comprises an A shaped iron core 12, having a primary coil 14 wound on the cross member 13, and a secondary coil 16, wound on the cross member 15. The primary coil 14 is connected in a high voltage circuit, as for example the usual 110 volt household circuit, one side being connected to the line wire 20 and the other side to the wire 22, safety switch 24 and line wire 25. The primary coil is adapted to be energized at all times, except when the safety switch 24 may be opened.

A control circuit, adapted to be energized by the secondary coil 16, may be traced, starting at one side of the secondary coil 16, through wire 28, contact arm 66 of a room thermostat 60, contacts 68 and 72, contact arm 70 and wire 78, heater coil 30, wire 31, heater coil 32, contacts 56 and 54 of switch 34 and wire 36. The secondary coil 16 has fewer turns than the primary coil 14 so that a low voltage current is induced in the secondary coil, when the control circuit is closed, as is well understood in the electric art. An armature 38, pivotally supported on a leg 45 of the transformer core 12, is adapted to be magnetically attracted to a similar opposite leg 46 when the circuit of the secondary 16 is closed. The magnetic attraction is provided by the flow of flux in a path from the leg 45, through the armature and across to the leg 46, established due to a counterflux created in the cross member 15 when the secondary coil 16 is energized, which causes the flux to take the path described above. When the secondary circuit is opened, the armature is adapted to drop away from the leg 46 by the force of gravity. The armature 38 is provided with an extension 40, preferably of a dielectric material, upon which is mounted a pair of contact bars 42 and 44 of switches 47 and 49 and are adapted to bridge two sets of stationary contacts 48 and 50, respectively, when the armature is raised against the leg 46. Bridging the contacts 48 and 50 closes the switch 47 which controls the fuel burner motor 8 and the ignition transformer 90, and a holding circuit switch 49 connected in the control circuit. These circuits will be traced hereinafter. The armature 38 also carries a contact arm 52, which is preferably formed of spring metal, having the contact 54 of switch 34 on the end thereof. The contact 54 is adapted to engage the contact 56 carried on a thermostatic element 88, to be described later. Thus the device 10

serves a dual purpose of providing a transformer for the low voltage control circuit and a relay device for controlling the fuel feeding motor and the control circuit.

5 The operation of the transformer relay 10 is controlled by the room thermostat 60, which is connected in the low voltage circuit. The thermostat 60 comprises a bimetal strip 62 anchored at one end, as at 63, and having a contact 64 carried on the opposite end. A contact carrying arm 66, preferably of spring metal, is anchored at one end and has a double contact member 68 carried thereon adjacent the free end. The contact arm 66 is normally biased against an adjusting screw 69, which forms a stop therefor. A second contact arm 70, also of spring metal, and normally biased against a fixed stop 73, is anchored at one end, and has a contact 72 on the free end thereof. The bimetal strip 62 is connected by the wire 75, to one of the contacts 50 of switch 49. The contact arm 66 is connected to the wire 28, and the contact arm 70 is connected in the low voltage circuit by the wire 78. The temperature at which the thermostat 60 operates to energize the transformer relay device 10, may be adjusted by a hand screw 59 which is adapted to vary the position of the bimetal with respect to the contact 68, and consequently vary the temperature at which the bimetal will engage 20 the contact 68. The operation of the thermostat 60 will be described hereinafter.

35 A timing mechanism, provided for delaying the closing of the switch 34, comprises a bimetallic strip 80 suitably anchored at one end, as at 81, having the contact 56 secured to the free end thereof. The side of the strip 80 having the lowest coefficient of expansion is uppermost, so that the heat generated by the heater element 32, connected in the low voltage circuit and disposed 40 in heat transfer relation with the bimetallic strip 80, will cause the bimetallic strip 80 to flex upwardly against a stop 82. The bimetallic strip 80 is preferably relatively massive so that it will cool relatively slowly and remain against the 45 stop 82 for several minutes after deenergization of the heater coil 32.

An ignition device, indicated at 89, is adapted 50 to be energized by an ignition transformer 90. The circuit of the primary 91 of the transformer 55 may be traced from high voltage line 25, safety switch 24, wire 22, wire 7, primary 91, ignition switch 92, wires 6 and 11, motor switch 47 and line wire 20. The ignition switch 92 is a toggle operated switch and comprises two oppositely disposed switch members 93 and 94 which are pivoted each at one end in suitable pivot means, such as the V shaped notches 96 formed in a 60 suitable bracket member 97. A tension spring 100 is connected adjacent the free ends of the members 93 and 94, for biasing the members to one side or the other of the dead center position of the members established with respect to the spring 100. The free end of the member 93 has a contact bar 102 suitably secured thereto 65 through an insulated part which is adapted to bridge contacts 104 to close the switch 92. The free end of the member 94 is limited in movement between the upper and lower surfaces of a recess 106 provided in a sliding member 108. The contact carrying member 93 is limited in movement 70 by the contacts 104 and the end of a relatively light weight push rod 110, which is adapted to slide vertically in suitable guides 109 and is so disposed as to be engaged by the under side of 75 the armature 38. The switch 92 is adapted to be

opened by the upward movement of the member 108, which raises the end of the member 94 until the center of the spring 100 is moved above the pivot of the member 94, whereupon the tension of the spring 100 causes the member 94 to be snapped to the upper surface of the recess 106. This throws the center of the spring 100 above the pivot of the member 93, thereby causing the spring 100 to snap the member 93 against the push rod 110, raising the latter against the 10 armature as shown in Fig. 2 and opening the switch. The switch is adapted to be closed by the push rod 110 when the armature 38 drops, due to the opening of the control circuit. Thus the ignition switch is always positively closed 15 when the motor circuit is opened. Slight movement of member 108 downwardly moves the free end of the member 94 downwardly so that the center of the spring 100 moves below the pivot of the member 94 and thereby causes the member 94 to be snapped against the lower surface of the stop 106 by the tension of the spring 100.

The safety switch designated generally at 24, is connected in the high voltage circuit, and in series with the primary 14 of the transformer 25 relay 10, the ignition circuit and the motor circuit and is constructed similarly to the ignition switch 92, having two oppositely disposed switch members 111 and 112 pivoted at 113, with a spring 115 connecting the members adjacent their 30 free ends. A contact bar 120, is carried on the free end of the member 111, and is adapted to bridge contacts 124. The free end of the member 112 is limited in movement between the stop 116 and a shoulder 119 located on the slide member 108, and the end of the member 111 is limited in movement between the contacts 124 and a stop 117. The safety switch 24 is adapted to be opened by the upward movement of the member 108 which moves the member 112 upwardly 40 until the spring 115 is moved above the pivot of the member 112, whereupon the tension of the spring 115 snaps the member 112 upwardly against the stop 116. This movement throws the center of the spring 115 above the pivot of 45 the member 111 and the tension in the spring 115 snaps the member 111 upwardly against the stop 117, thus opening the switch at the contacts 124. To reclose the safety switch, the member 112 must be moved manually to the shoulder 119 50 when the member 108 is in its lower position, so that the spring 115 will be moved below the pivot of the member 111 and snap the member 111 downwardly and close the contacts 124. When the switches 24 and 92 are closed and the burner 55 system is inoperative, the member 112 forms a greater angle with the horizontal plane than the corresponding member 94 of the switch 92 so that an equal upward rate of movement of the ends of the members 94 and 112 will cause the switch 60 92 to be opened prior to the opening of the switch 24.

The slide member 108 is adapted to be moved in a vertical plane, by a timing device, to operate the switches 92 and 24. Member 108 is guided 65 by guides 118. The timing device comprises a bimetal member 140, anchored at one end, as at 142, having the heating element 30 disposed in heat transfer relation therewith. The free end of the bimetal 140, extends into a recess 144, 70 formed in the slide member 108. The side of the bimetal having the lowest coefficient of expansion is uppermost, so that when the heater 30 is energized, the bimetal will flex upwardly, moving the sliding member 108 therewith. The 75

bimetal 140 is adapted to cool readily and assume its normal position as shown in Fig. 1, shortly following deenergization of the heater 30, moving member 108 against a stop 107. The upward movement of the member 108 is adapted to be arrested, at a predetermined point, by a combustion responsive device 150, such as a device that is responsive to temperatures produced in the stack of the fuel furnace. The device 150 comprises a spiraled bimetal element 152, preferably placed in the stack of the furnace, which is adapted when heated, to rotate a rod 154 clockwise. A crank member 156, having a slide bar 158 slidably connected thereto, is connected to the end of the rod 154 by the usual friction clutch, well known in the stack control art. The slide bar 158 is adapted to be moved longitudinally between guides 160 by the rotation of the crank member 156, into or out of the path of travel of the lower surface 162 of a detent 121 formed in the member 108 as soon as there is a slight change in temperature in the stack. When the bar 158 is moved to the right it is engaged by the surface 162 thereby arresting further upward movement of the member 108. The bimetal 152 is adapted to rotate the rod 154 clockwise when it is heated, and consequently move the bar 158 to the right, and on cooling, to move the bar 158 to the left. The detent 121 is positioned so that the upward movement of the member 108 may be arrested after the ignition switch 92 has been opened, but before the safety switch 24 is opened.

The operation of the control system is as follows: Assuming the apparatus to be temporarily inoperative, the parts will be as shown in Fig. 1, and when the room containing the thermostat 60 cools, the bimetal 62 will flex to the right due to the decrease in temperature, and the contact 54 will move against the left surface of contact 68. This, however, does not complete the control circuit but on continued cooling of the room the bimetal 62 will continue to flex until it moves the contact 68 against the contact 72. A circuit 40 is then established through the secondary 16, wire 28, contact arm 66, and contacts 68 and 72, contact arm 70, wire 78, heater element 30, wire 31, heater element 32, contacts 56 and 54, arm 52, and wire 36. The closing of the control circuit 50 causes the transformer relay 10 to attract the armature 38 to the leg 46, thereby closing the switches 47 and 49. The switch 47 establishes a circuit for the fuel feeding motor 8 which may be traced as follows: line wire 25, safety switch 24, wires 22 and 26, motor 8, wire 11, switch 47 and line wire 20. The motor 8 thereby energized, operates to pump fuel into the furnace and to supply the necessary air to support combustion. The ignition device 89 is energized at the same time since the switch 92 is in its closed position and connected in parallel with the motor 8 and through the motor switch 47.

The switch 49 establishes a holding circuit around the contacts 68 and 72, and connects contacts 64 and 68 in the low voltage circuit, so that the low voltage circuit will not be opened until after the contacts 64 and 68 have separated. The holding circuit may be traced through the secondary coil 16, wire 28, contacts 68 and 64, of room thermostat 60, wire 15, contacts 50 and 44, wires 9 and 78, heater 30, wire 31, heater 32, contacts 56 and 54, and wire 36. Thus the secondary circuit is maintained closed although contact 68 separates from contact 72.

The closing of the secondary circuit energizes

the heater coil 32, which causes the bimetal 80 to flex upwardly against the stop 82. The flexible contact arm 52, placed under stress by the movement of the armature 38, causes the contact 54 to follow the contact 56 as the bimetal 80 flexes upward, to maintain the switch 34 closed. The heater 30 is also energized and within several seconds causes the bimetal element 140 to move slowly upward, moving the bar 108 therewith. A predetermined upward movement of the member 108 opens the switch 92 which deenergizes the ignition device. The time required for the bimetal 140 to be heated sufficiently to cause opening of the switch 92, is such that under normal conditions the fuel of the burner should be ignited. The establishment of combustion causes the bimetal 152 to become heated by the products of combustion and thereby cause the bar 158 to be moved into the path of travel of the shoulder 162 arresting upward movement of the member 108, to prevent opening of the safety switch 24. After combustion is established, the room thermostat is warmed to a predetermined degree, the bimetal 62 is flexed to the left, and upon initial movement thereof, contacts 78 and 72 will be separated. This separation, however, will not affect the circuit due to the holding circuit established around these contacts by the switch 49, as described above. As the bimetal 62 flexes further to the left due to continued warming thereof, the contact arm 66 finally rests against the screw stop 69 and the contact 64 will then separate from contact 68 and break the control circuit. The opening of the control circuit causes the armature 38 to drop, opening switches 47, 49, and 34 and closing the ignition switch 92, as described above. The contact 54 carried by the armature 38, will drop from the contact 56, but the switch 34 will remain open since the bimetal 80 remains flexed against the stop 82, 40 by the heat already transmitted thereto from the heater 32. The bimetal 80 will require several minutes to cool and will then assume its position as shown in Fig. 1. This time lapse permits purging of the fuel burning system of any unburned fuel that might have collected in the furnace.

When armature 38 drops, it will move the ignition switch arm 93 downwardly and either close the switch 92 or move the arm to a position in which it will be snapped closed upon a slight lowering of the toggle arm 94. The thermostat 140 is arranged to move the slide bar 108 downwardly far enough to cause the arm 94 to be moved beyond its dead center position, i. e. to a position in which it retains the switch 92 closed, before thermostat 80 cools to the temperature at which it closes contact 56 on contact 54. Therefore, after a cessation of operation of the fuel burning apparatus, the ignition circuit is closed at switch 92 before the secondary or control circuit is complete and the toggle mechanism for the switch 92 insures ignition for a time sufficient for restarting the fuel burning apparatus. Thus it is apparent that the ignition circuit will be conditioned for operation at switch 92 before the secondary circuit is energized. Therefore, in the event that the room thermostat is readjusted for a warmer room temperature immediately after it has opened the control circuit, the closing of the circuit is nevertheless delayed for an interval of predetermined time from the time that the room thermostat last opened the control circuit. This time delay is sufficient, not only for insuring that the igni- 75

- tion switch 92 will be closed but also sufficient for purging the combustion chamber.
- If combustion should not occur, for any reason, after the fuel feeding motor has been energized, the stack device 150 would be inoperative due to the absence of combustion, the member 108 would be moved upwardly until the safety switch causes deenergization of the transformer relay 10, the ignition circuit and the motor circuit.
- Should combustion cease, for any cause, after once being established, the stack thermostat 150 will immediately cool and cause the bar 158 to be withdrawn from the stop 162 substantially immediately after a slight change in temperature of the stack, whereupon the bimetal 140, being biased upwardly by the heat of the heater 30, will immediately move the member 108 upward to cause opening of the safety switch and deenergization of the entire system, which remains so until the safety switch is manually reset, as described above.

While the form of embodiment of the present invention as herein disclosed constitutes a preferred form, it is to be understood that other forms might be adapted, all coming within the scope of the claims which follow.

I claim:

1. A control system for a fuel burning device, comprising in combination, electrically operated means for controlling the fuel burning device; a circuit for said means including a switch; an electromagnet for closing the switch; an ignition circuit; electrical timing means including mechanism for opening the ignition circuit after a determined time of operation thereof; a control circuit for the electromagnet including a switch, said electromagnet being movable when deenergized to open said switch; said electromagnet and timing mechanism cooperating to condition the ignition circuit for operation a predetermined time after deenergization of the control circuit, said timing mechanism being movable from one position to another for closing the second switch and being timed to prevent the reclosing of the second switch prior to conditioning of the ignition circuit and returnable to the said one position when the control circuit is reenergized; and means for controlling the control circuit.
2. In a fuel burning system, in combination, a fuel feeding device; a control circuit for said device; a switch in said circuit; electrically operated means for operating the switch; a control circuit for said electrically operated means; a switch in said control circuit; an ignition circuit including a switch therein; timing means rendered operable by the control circuit to open said ignition switch within a predetermined period after energization of the fuel feeding device; means for opening the second switch upon deenergization of the fuel feeding device; and timing means for reclosing the said second switch; said first mentioned timing means including means for reclosing the ignition switch, and said last mentioned timing means being adapted to reclose the second switch subsequent to the reclosing of the ignition switch.
3. A control system for a fuel burning apparatus, comprising in combination, electrically operated means for actuating the fuel burning apparatus; a control circuit for said means; an

ignition device and a circuit therefor; means for controlling the ignition circuit including a switch, movable means associated with the ignition switch and having a position for retaining the ignition switch closed and movable to a second position for opening the ignition switch, timing mechanism for moving the movable means from the first position to the second position within a predetermined time, and from the second position to the first position within a predetermined time, said timing mechanism being rendered operative and inoperative by the control circuit; said control circuit including a switch therein arranged to be opened when the fuel burning apparatus is rendered inoperative by the control circuit; and a second timing mechanism for reclosing the switch in the control circuit, the first and second mentioned timing mechanism being so computed that the movable member is in the first mentioned position when the second mentioned timing mechanism recloses the switch in the control circuit.

4. In a fuel burning system; electrically operated fuel feeding means; an electrically operated device for controlling said fuel feeding means; a control circuit for said device having a switch therein; means including a time operated device for opening the switch when the fuel feeding device is deenergized and for closing the switch a predetermined time after deenergization of the fuel feeding means; an ignition circuit including a switch; means including a time operated device for opening the said last switch a predetermined time after energization of the fuel feeding means and for closing the said switch prior to the closing of the first mentioned switch.

5. In a fuel burning system; electrically operated fuel feeding means; an electrically operated device for controlling said fuel feeding means; a control circuit for said device having a switch therein; means including a time operated device for opening the switch when the fuel feeding device is deenergized and for closing the switch a predetermined time after deenergization of the fuel feeding means; an ignition circuit including a switch; means including a time operated device for opening the said last switch a predetermined time after energization of the fuel feeding means and for closing the said switch prior to the closing of the first mentioned switch, said time operated devices comprising an electroresponsive thermostat connected in the control circuit.

6. In a fuel burning system, in combination, a fuel feeding device; a control circuit for said device; a switch in said circuit; electrically operated means for operating the switch; a control circuit for said electrically operated means; a switch in said control circuit having a timing mechanism associated therewith, said switch being opened by the electrically operated means, and closed by said timing device a determined time after the opening thereof; an ignition circuit including a switch; means including timing mechanism for causing the opening of the switch a predetermined time after energization of the ignition circuit, the said last means being adapted to reclose the ignition switch prior to the closure of the second mentioned switch.
